CLAIM

The ornamental design for a multitool, as shown and described.

DESCRIPTION

FIG. 1 is a top perspective view of a multitool, showing our new design in a fully retracted configuration;

FIG. 2 is a bottom perspective view of FIG. 1;

FIG. 3 is a front elevational view of FIG. 1;

FIG. 4 is a rear elevational view of FIG. 1;

FIG. 5 is a right-side elevational view of FIG. 1;

FIG. 6 is a left-side elevational view of FIG. 1;

FIG. 7 is a top plan view of FIG. 1;

FIG. 8 is a bottom plan view of FIG. 1;

FIG. 9 is a top perspective view thereof, illustrated in an expanded configuration;

FIG. 10 is a bottom perspective view thereof;

FIG. 11 is a front elevational view thereof;

FIG. 12 is a rear elevational view thereof;

FIG. 13 is a right-side elevational view thereof;

FIG. 14 is a left-side elevational view thereof;

FIG. 15 is a top plan view thereof;

FIG. 16 is a bottom plan view thereof;

FIG. 17 is an exploded top perspective view thereof;

FIG. 18 is an exploded right-side elevational view thereof;

and,

FIG. 19 is an exploded left-side elevational view thereof.

The broken lines in the figures depict portions of the multitool that form no part of the claimed design.
